C. H. DUFFY,
SPARK PLUG,
APPLICATION FILED JULY 30, 1917.

Patented Mar. 26, 1918.

Charles Hugh Duffy Inventor

UNITED STATES PATENT OFFICE.

CHARLES HUGH DUFFY, OF CHEVY CHASE, MARYLAND.

REISSUED

SPARK-PLUG.

1,260,684.

Specification of Letters Patent. Patented Mar. 26, 1918.

Application filed July 30, 1917. Serial No. 183,529.

To all whom it may concern:

Be it known that I, CHARLES HUGH DUFFY, a citizen of the United States, residing at Chevy Chase, in the county of 5 Montgomery and State of Maryland, have invented certain new and useful Improvements in Spark-Plugs; and I do declare the following to be a full, clear, and exact description of the invention, such as will enable others skilled in the art to which it appertains to make and use the same, reference being had to the accompanying drawings, and to the letters and figures of reference marked thereon, which form part of 10 this specification.

This invention relates to spark plugs for internal combustion engines, and has for its object to provide a device of this class which embodies improvements in the method, construction and arrangement for seating and maintaining the insulating core within the metal shell of the plug to prevent leakage of pressure.

The invention consists in the novel construction and arrangement of the core holding gland and in the method for effecting the retention of the core within the same and of effecting a gas tight union between the gland and the metal shell and between 25 the gland and the core.

Referring to the accompanying drawings:—

Figure 1 is a vertical sectional view of a spark plug constructed in accordance with 30 this invention.

Fig. 2 is a fragmentary sectional view illustrating the manner of assembling the gland and core in the shell.

Fig. 3 is an elevation of the gland and 35 core after being assembled.

Fig. 4 is an elevation of the gland before entering the shell.

Fig. 5 is a bottom plan view of the shell, and

Fig. 6 is a vertical sectional view showing the shell, gland and core in an assembled position.

Like numerals of reference indicate the same parts throughout the several figures, in 40 which:—

1 indicates the spark plug comprising the threaded metal shell 2, gland 3, insulating core 4, central electrode 5 and ground electrode 6.

55 The core 4 has an enlarged central ring 9

forming a flat shoulder 10 at its top and preferably a 45° shoulder 11 at its bottom, and is centrally apertured at 16 to receive the threaded central electrode 5.

Referring to the gland 21, it will be seen 60 that the same is provided with a flattened portion 22, a depending thin tubular or thimble portion 23 and an intermediate threaded portion 24 for connection with the internally threaded shell 2, while internally of the 65 gland 21 at the beginning of the thin tubular portion 23 is a shoulder 25, the edge of said portion 25 being preferably rounded at 26.

The shell 2 is externally threaded at 27 for connection with a motor, and is provided 70 intermediate its ends with a downwardly inclined annular shoulder 28, the shell being apertured to receive the core 4 and gland 21 in the manner as shown in Fig. 1.

In assembling the plug, the core and central electrode are secured in proper position and the core 4 is placed in the gland 21, a gasket 35 being preferably provided between the shoulder 10 of the core 4 and the shoulder 25 of the gland 21, the thin depending tubular portion 23 extending slightly beyond the inclined shoulder 11 of the core, while a gasket 26' is placed as shown in Fig. 2. When in this position the gland 21 and core 4 are inserted in the shell 2, the operation being facilitated if the parts are held upside down. The gland 21 is threaded into, the shell 2 so that the rounded edge 26 of the tubular extension 23 impinges on the inclined shoulder 28 as shown in Fig. 2. 90

Further rotation of the gland 21 causes it to progress inwardly of the shell 2, and the rounded edge 26 of the gland 21 is gradually spun inwardly, as shown in Fig. 3, by the shoulder 28 until the entire end portion 26 95 of the thin tubular portion 21 is spun on the inclined shoulder 28 until the entire end portion 26 of the thin tubular portion 23 is spun under the gasket 36' and the inclined shoulder 11 of the core 4. As this spinning 100 operation is being effected and the inward progress of the core 4 is being retarded by the turning under of the tubular portion 23, the gaskets 35 and 36' are compressed. As the portion 26 is spun under the shoulder 105 11 of the core, as it is being rotated on the inclined shoulder 28 of the shell, said portion 26 conforms to the said shoulder 28 and grinds a bearing thereon in such manner that a gas tight union is formed between the 110

shoulder 28 and the spun portion 26, while a gas tight joint is simultaneously effected between the core 4 and the gland 21, at the gaskets 35 and 36'. This method of spinning the gland directly on the inclined shoulder 28 of the shell 2 presents the advantage that an absolute conformation of the spun portion 26 with the shoulder 28 is produced and a ground bearing effected which is not so obtained by spinning the gland on the core 4 by usual mechanical means, as in the ordinary manner there would be no assurance of a gas tight joint and the employment of a gasket between the portion 26 and the shoulder 28 would be quite necessary.

Having thus fully described the invention what I claim and desire to secure by Letters Patent of the United States is:—

- 20 1. A spark plug comprising a metal shell threaded for connection with a motor and having an internal bore, and an internal shoulder, an insulating core and suitable electrodes, a gland for connection with said shell, a tubular portion on said gland and an internal shoulder, said tubular portion being adapted to receive said insulating core, the end of said tubular portion being adapted to engage the said shoulder in said shell to spin said end of said tubular portion under said insulating core and between the same and said shoulder in said shell.
- 25 2. A spark plug comprising a metal shell having a bore therein and an internal shoulder, an insulating core having a central ring forming an upper and a lower shoulder, a gland for connection with said shell and having an internal shoulder and a tubular portion to receive said insulating core, the lower end of said tubular portion being adapted to engage said shoulder in said shell to spin the same under said ring and between the same and said shoulder in said shell.
- 30 3. A spark plug comprising a metal shell having a shoulder therein, an insulating core having a ring thereon, a gland having a shoulder therein and a tubular portion to receive said insulating core, said tubular portion being adapted to engage and rotate on said shoulder in said shell to spin said tubular portion under said ring and to grind a gas tight joint between the spun tubular portion and said shoulder in said shell.
- 35 4. A spark plug comprising a metal shell having a shoulder therein, a gland for connection with said shell, an insulating core to be received by said gland, a tubular portion in said gland adapted to engage said shoulder in said shell and to rotate thereon to spin the tapered portion under said insulating core.
- 40 5. A spark plug comprising a shell, an

insulating core and a gland provided with a 65 tubular portion adapted to receive said insulating core, means within said shell to be engaged by said tapered portion of said gland to spin the same around said insulating core upon the inward progression of 70 said gland within said shell.

6. A spark plug comprising a shell having a shoulder therein, an insulating core having a ring thereon forming an upper and a lower shoulder, a gland for connection with said shell and provided with an internal shoulder and a tubular portion, said insulating core being adapted to be received by said gland, packing means between the shoulder in said gland and the upper 80 shoulder in said insulating core, the said tubular portion of said gland being adapted to engage said shoulder in said shell and to rotate thereon to spin said tubular portion under the lower shoulder of said insulating 85 core and to grind a gas tight joint between the shoulder in said shell and the tubular portion of the gland.

7. The herein described method of seating an insulating core in a spark plug shell 90 with consists in inserting the insulating core in a threaded gland or bushing, in threading the gland or bushing into the spark plug shell to rotate the gland or bushing against a shoulder in the spark plug shell to spin the said gland or bushing under the insulating core and between the same and the shoulder in the spark plug shell.

8. The herein described method of seating an insulating core in a spark plug shell, 100 which consists in providing a spark plug shell with an internal shoulder and in providing a core retaining gland with a thin tubular portion, in inserting the insulating core within its retaining gland and in rotating the gland against the shoulder in the shell to spin the tubular portion of the gland between the insulating core and the shoulder in the spark plug shell.

9. The herein described method of seating 110 an insulating core in a spark plug shell which consists in relatively rotating a threaded core retaining gland within and with relation to a spark plug shell to relatively progress the core retaining gland 115 against a shoulder in the spark plug shell to spin the core retaining gland between the insulating core and the shoulder in the spark plug shell.

10. The herein described method of seating 120 an insulating core in a spark plug shell which consists in relatively progressing a threaded core retaining gland inwardly of a spark plug shell and against a shoulder therein to distort the said threaded core retaining gland and spin the same between the insulating core and the spark plug shell.

11. The herein described method of re-

taining an insulating core within a spark plug gland, which consists in relatively progressing a threaded core retaining gland inwardly of a shell and against a shoulder 5 therein, to distort the said threaded core retaining gland and spin the same between the insulating core and the shoulder in the shell.

In testimony whereof I affix my signature in presence of two witnesses.

CHARLES HUGH DUFFY.
